UNITED STATES PATENT OFFICE.

ALBERT WAHLE, OF BROOKLYN, NEW YORK, ASSIGNOR TO CASSIDY & SON MANUFACTURING CO., A CORPORATION OF NEW YORK.

DESIGN FOR A HANGING LAMP OR SIMILAR ARTICLE.

51,401.

Specification for Design.

Patented Oct. 16, 1917.

Application filed May 14, 1917. Serial No. 168,614. Term of patent 7 years.

To all whom it may concern:

Be it known that I, ALBERT WAHLE, a citizen of the United States, and a resident of the borough of Brooklyn, county of Kings, and city and State of New York, have invented a new, original, and ornamental Design for Hanging Lamps or Similar Articles, of which the following is a specification, reference being had to the accompanying drawing, forming part thereof.

The said drawing is a view of a hanging lamp or similar articles, showing my new design.

Copies of this patent may be obtained for five cents each, by addressing the "Commissioner of Patents, Washington, D. C."

I claim:

The ornamental design for a hanging lamp or similar articles, as shown.

In witness whereof I have hereunto signed my name this 19th day of April, 1917, in the presence of two subscribing witnesses.

ALBERT WAHLE.
